UNITED STATES PATENT OFFICE.

POLETE PARRETT, OF WILLOW SPRINGS, MISSOURI.

PICTURE-FRAME.

SPECIFICATION forming part of Letters Patent No. 276,624, dated May 1, 1883.

Application filed September 25, 1882. (No model.)

To all whom it may concern:

Be it known that I, POLETE PARRETT, of Willow Springs, in the county of Howell and State of Missouri, have invented certain new and useful Improvements in Picture-Frames; and I do hereby declare that the following is a full, clear, and exact description of the invention, which will enable others skilled in the art to which it appertains to make and use the same, reference being had to the accompanying drawings, which form a part of this specification.

This invention relates to frames for pictures, looking-glasses, and the like, and has for its object to provide an ornamental and efficient frame that can be readily taken apart or set up, so as to be contracted in size or filled out to receive a larger picture or the like.

In the drawings, Figure 1 is a perspective view of a portion of one of my improved frames; and Figs. 2, 3, 4, 5, 6, and 7 are like views of the strips of which the frame is constructed. Fig. 8 is an inner edge view. Fig. 9 is a perspective view of the ends of the chain. Fig. 10 is a detail view.

Referring to the drawings, A designates a flat piece or strip, having a slot, *a*, at its center, a straight edge, *a'*, and shoulder *a''* on its opposite edge.

B is a similar strip, having a thin or narrow portion, *b*, near its center, in which is formed a notch, *b'*, and a beveled opposite edge, *b''*. Strip B is the mate to strip A.

C is another strip, having a straight edge, *c*, in which is formed a notch, *c'*, and a beveled opposite edge, *c''*, forming a high shoulder, *c'''*.

D is the strip which is mated with strip C. It is formed with a slot, *d*, about midway, and with a straight edge, *d'*, forming a high shoulder, *d''*.

E is a similar strip of the pair E F, and is formed with a small notch, *e*, in one edge, and a larger notch, *e'*, forming a large shoulder, *e''*, in the opposite edge. The remaining strip, F, is formed, like strip D, with an about midway slot, *f*, and straight edge *f'*, forming a high shoulder, *f''*.

The above-described pieces are preferably formed of wood or like material, and may be inlaid at their projecting portions. Each strip

has an ornamental head, G, and a point, H, at its smaller end.

In forming my improved frame the strips are first arranged to make a chain the ends of which are afterward joined together. This is effected as follows: Strip A is held in the left hand by its end H, with its edge *a'* up and shoulder *a''* down. The point of strip C is then inserted from the right-hand side into the slot *a* and passed up until its shoulder *c'''* abuts against strip A, when the strip C is turned, so that its shoulder *c'''* is down and the small notch *c'* is embracing strip A. (See Fig. 9.) The strip D is now also placed in slot *a*, with its straight edge *d'* against the flat side of C, and its shoulder *d''* abutting against strip A. The pair of strips C and D are thus secured in strip A at right angles to each other. Strips E and F are now inserted into strip D in a manner similar to the way strips C and D were inserted into strip A, which manner is as follows: Strip E is inserted into slot *d* and turned round, so that its shoulder *e''* will abut against strip D, and its notch *e* will embrace the strip D, the flat broad side of strip E being now against strip A. Strip F is now inserted, like strip D, in slot *d*, with its straight edge *f'* against the flat side of E, and its shoulder *f''* abutting against strip D. The pair of strips E and F are thus at right angles to each other, and the pair are inclined in a direction contrary to that of the pair C and D. (See Fig. 10.) The strip B is now inserted into the slot *f*, and turned so that its notch *b'* will embrace strip F, after which another strip, A, is inserted into slot *f* at right angles to strip B, when another series of strips are arranged as and in the order above named, and so on until a chain of the desired length is completed. The chain when completed will be flexible, and can readily be bent into a circle or oval or other shape, when the ends are connected by passing the first-placed strip, A, through the slot *f* of the last strip F against the last strip B. The shoulder *a''* of strip A enters slot *f* and abuts against strip F, as shown. The inner edge of the frame is formed by the pointed ends of pieces A, B, C, and D, and the edges of pieces B and C are beveled, *b''* *c''*, so as to better hold a ring, I, for holding the pictures, glass, &c.

The thin portion *b* of strip B admits of the strip A readily entering the same slot.

I claim as new—

In a frame, the combination of strip A, having slot *a* and shoulder *a''*, strip B, having notch *b'*, strip C, having notch *c'* and shoulder *c'''*, strip D, having slot *d* and shoulder *d''*, strip E, having notch *e* and shoulder *e''*, and strip F, having slot *f* and shoulder *f''*, as set forth.

In testimony that I claim the foregoing as my own I have hereto affixed my signature in presence of two witnesses.

POLETE PARRETT.
